UNITED STATES PATENT OFFICE.

CHARLES H. BOGART, OF NEW YORK, N. Y.

MOUTH-GUARD FOR BOTTLES.

SPECIFICATION forming part of Letters Patent No. 644,891, dated March 6, 1900.

Application filed June 30, 1899. Serial No. 722,422. (No model.)

To all whom it may concern:

Be it known that I, CHARLES H. BOGART, of the city of New York, borough of Brooklyn, in the county of Kings and State of New York, 5 have invented a new and Improved Mouth-Guard for Bottles, of which the following is a full, clear, and exact description.

One object of my invention is to provide a means whereby the mouths of bottles may be 10 protected from fracture as the result of careless handling and also to utilize such protective appliance as a means for identifying, even in the dark, bottles belonging to a certain proprietor or firm.

15 Another object of the invention is to attain the result above set forth in a simple and economic manner and without in the least interfering with the proper action of the cover or sealing device employed.

20 The invention consists in the novel construction and combination of the several parts, as will be hereinafter fully set forth, and pointed out in the claims.

Reference is to be had to the accompanying 25 drawings, forming a part of this specification, in which similar characters of reference indicate corresponding parts in both figures.

Figure 1 is a vertical section through the upper portion of a milk-bottle and likewise a 30 vertical section through the improved device applied to the bottle; and Fig. 2 is a vertical section through the guard removed from the mouth of the bottle, the guard, however, being bent in the same position it would occupy 35 if applied to a bottle.

The bottle A is an ordinary milk-bottle, and the said bottle is provided with the usual cap or cover B, operated through the medium of the ordinary lever-bail C.

40 The improvement consists in a band 10, and said band is preferably made of rubber or other yielding material and may be solid, as illustrated, or the said band may be bent upon itself to form vertical parallel members, if desired. A wire ring 11 is located in the upper portion of the said band 10. This wire ring is of a diameter less than the outer diameter of the upper or bearing edge of the mouth of the bottle and of greater diameter than the 45 interior diameter 12 of the mouth, so that when the band 10 is placed upon the upper portion of the neck of a bottle the said band will be immediately over the central portion

of the upper edge of the mouth, as shown at 13 in Fig. 1, or will occupy an equivalent position, while the body of the band 10 is sprung over the outer surface of the upper portion of the neck of the bottle, and the said band is of such width that it will extend beyond the usual exterior shoulder 14, formed at the 55 upper portion of the neck of a milk-bottle, as illustrated in Fig. 1; and, furthermore, the protective band 10 is secured to the neck of the bottle by means of wiring 15, although other means may be employed, if desired. 60 Thus it will be observed that the band 10 protects the outer surface of the upper portion of the neck of the bottle and likewise the outer edge of its mouth, effectually preventing these parts from becoming chipped, and at the same 65 time the cap or cover B, usually employed for a milk-bottle, may rest in the ordinary way upon the mouth of the bottle, as shown in Fig. 1, the cap or cover B fitting snugly within the inner upper margin of the said band 10. 70 75

The band 10 serves a dual purpose, since it not only protects the mouth of the bottle from breakage, but acts also as a means of identification, as a milkman in the dark by touching a bottle provided with the improved 80 band may identify it from other or ordinary bottles. A band of the character set forth may also act somewhat in the nature of a trademark, indicating to purchasers that they 85 really have received milk from a particular firm or individual.

Having thus described my invention, I claim as new and desire to secure by Letters Patent—

1. The combination with the bottle, of a 90 yielding band surrounding the neck of the bottle and also engaging the top edge thereof, and a rigid ring embedded in said band at the top edge thereof and of a diameter intermediate between the inner and outer diameters of the bottle's mouth.

2. A mouth-guard for bottles and the like, comprising a yielding band forming a tube open at the top and at the bottom, said band being cylindrical in its lower portion and contracted at its upper edge, and a rigid ring embedded in said band at the upper edge thereof.

CHARLES H. BOGART.
